MACHINE FOR TAPERING SHEET METAL
BLANKSHarry J. Horn, Lansing, Mich., assignor to Motor
Wheel Corporation, Lansing, Mich., a corpora-
tion of Michigan

Application July 30, 1948, Serial No. 41,601

2 Claims. (Cl. 80—16)

1

This invention relates to a machine for tapering sheet metal blanks and in particular for tapering sheet metal blanks preparatory to forming the bodies of vehicle wheels therefrom.

It is an object of the invention to produce a machine for tapering vehicle wheel body blanks which is efficient, simple in structure, and economical in operation.

In the drawings:

Fig. 1 is an elevation partly in section showing my machine for tapering wheel disc blanks.

Fig. 2 is a section along the line 2—2 of Fig. 1.

Fig. 3 is a fragmentary section showing in detail the pilot for the disc.

My machine comprises a base 1, a head 2 supported on the base by a plurality of posts 3. A movable head 4 is supported on piston 5 which is reciprocably mounted in cylinder 6. A plate 7 is secured to head 4 and a flat circular platen 8 is supported upon plate 7. A small plate 10 is carried on pilot 9 and arranged to move up and down in opening 11 positioned centrally of platen 8. The lower end 12 of pilot 9 is journalled in a central opening in plate 7 for both rotary and longitudinal movement. A compression spring 13 is housed in opening 14 in head 4 and acts between plate 15 and the lower end 16 of pilot 9 to urge pilot 9 upwardly so that the upper face of plate 10 normally is positioned above the upper face of platen 8.

Upward movement of pilot 9 is controlled by collar 17 secured by bolts 18 in the upper face of movable head 4. Collar 17 acts between shoulder 12 and shoulder 19 on pilot 9 to limit the upward and downward movement of pilot 9.

A ratchet 20 is fixed on pilot 9 and is arranged to be actuated by a pawl 21 pivoted as at 22 on rod 23 which is slidably mounted for radial movement in groove 24 in the upper face of plate 7. The outer end of rod 23 engages a bell crank lever 25 which is pivoted as at 26 on head 4 and contacts the upper end of vertical rod 27 fixed at its lower end to base 1.

A source (not shown) of liquid, such as oil, under pressure is supplied through pipe line 28 to a valve 29 and port 30 to cylinder 6. The liquid is exhausted from cylinder 6 through port 30, valve 29 and line 31.

The upper part of my tapering machine comprises two arms 32 and 33 which are pivoted at their upper ends as at 34 and 35 to head 2 to swing about horizontal parallel axes. Rollers 36 are journalled upon shafts 37 by means of roller bearings 38. Shafts 37 are fixed to the lower ends of arms 32 and 33 so that cylindrical rollers 36 rotate about axes parallel to axes 34 and 35.

2

Axes 34 and 35 are offset equal distances from the extended longitudinal axis of pilot 9, for example, perpendicular lines dropped from axes 34 and 35 to the upper face of platen 8 will intersect the upper face of platen 8 a substantial distance to the right and left of pilot 9.

Arms 32 and 33 are arranged to be swung in and out by a hydraulic motor comprising a cylinder 39, a piston 40 to which is affixed piston rod 41. Oil under pressure is admitted into cylinder 39 above piston 40 through line 42 and valve 43 which are connected to a source (not shown) of liquid under pressure. Liquid under pressure is admitted into cylinder 39 beneath piston 40 through line 44 and valve 45 which are also connected to said source of liquid under pressure. The lower end of rod 41, which reciprocates in a vertical path, is connected by means of a toggle lever comprising levers 46 and 47 with arms 32 and 33 respectively.

Levers 46 and 47 are pivoted to the lower end of piston rod 41 at 48 and 49 respectively. Levers 46 and 47 are each adjustably connected to their respective arms 32 and 33. Lever 46 is connected to arm 32 by means of collar 50 through which lever 46 passes, pin 51 journalled in bracket 52 fixed to arm 32. Collar 50 is fixed upon pin 51 and the adjusted position of lever 46 in collar 50 is controlled by lock nuts 54 threaded on lever 46 and arranged to clamp collar 50 therebetween. The pivotal connection between lever 47 and arm 33 is identical with the connection between arm 32 and lever 46 and therefore will not be described. The effective length of each lever arm 46 and 47 can be controlled, of course, by adjusting the arm in its respective collar 50.

The operation of my device is as follows: Arms 32 and 33 are of equal length and rollers 36 are of identical size. Arms 32 and 33 will be pivotally supported on head 2 so that axes 34 and 35 are offset equal distances from the longitudinal center of pilot 9. Valve 29 will be actuated to exhaust liquid from cylinder 6, thereby causing plate 4 to lower. As plate 4 lowers, rod 27 swings lever 25 clockwise thereby sliding rod 23 and pawl 21 to the right which in turn acts through ratchet 20 to index pilot 9 and disc 58 one step or notch counter-clockwise, as viewed in Fig. 2. The disc 58, which is to be tapered, is provided with a central opening which nicely fits the non-circular contour of pilot 9 so that rotary indexing of pilot 9 will cause corresponding indexing of plate 58. Plate 58, of course, will be mounted upon platen 8 and pilot 9 while head 4 is lowered. At this time spring 13 will hold pilot 9 and plate 10 upwardly.

at their uppermost limit so that the disc 58 does not touch platen 8.

Preferably piston 40 will be at the upper end of its stroke so that arms 32 and 33 are at the inner end of their stroke, full lines Fig. 1. Valve 29 is actuated to admit liquid into cylinder 6, causing plate 4 to rise, and disc 58 is brought against rollers 36 and spring 13 collapses as platen 8 moves up against the under face of disc 58. At this time valve 45 is opened to exhaust and liquid under pressure is admitted through valve 43 above piston 41, causing piston 41 to move on its downward stroke and act through rod 41 and toggle levers 46 and 47 to swing arms 32 and 33 and their rollers 36 outwardly.

As rollers 36 move outwardly they also move toward the upper face of platen 8 thereby tapering the disc. Each roller will roll or taper about one-eighth of the disc per pass of the roller.

Valve 43 will now be opened to exhaust and valve 45 opened to liquid under pressure so that piston 40 is moved upwardly thereby swinging the arms and rollers 36 inwardly. Valve 29 is now operated to lower head 4 whereupon indexing mechanism 20-27 indexes the plate 10 and disc about one-eighth of a turn. The above described operation is now repeated until a sufficient number of rolling passes have been made to complete the tapering of the disc whereupon the disc is removed.

Pivots 34 and 35 are each mounted upon blocks 60 slidably supported upon head 2 and adjustable thereupon by means of screw 61 and hand wheel 62. Thus, the degree of taper imparted to disc 58 can be controlled by adjusting fulcrums or pivots 34 and 35 toward or away from the extended longitudinal axis of pilot 9. Axes 34 and 35 are parallel to each other and to the upper plane surface of platen 8 which supports the blank 58.

From the above it is evident that the blank 58 is operated upon between the flat upper face of platen 8 and the rollers 36 which operate from adjacent the center of the blank toward the circumference of the blank, the rolls being further from the flat face of the platen when they are adjacent the center of the blank than when they are at the circumference of the blank.

For purposes of description I have shown two rollers spaced 180° apart and therefore as the rolls operate on the disc two segments of the disc are tapered simultaneously. After each pass of the rolls the blank is rotated by the indexing mechanism to present a new portion of the blank to the rollers and after a series of passes a complete blank is tapered. It should be noted that the distance between axes 34 and 35 is greater than the distance between the axes 37 of the rollers at the beginning of the outward rolling

pass so that when the arms 32 and 33 are forced apart by the hydraulically actuated toggle the rolls swing in an arc and toward the platen and thereby cause the disc to be tapered or rolled thinner from the center of the disc toward the circumference of the disc.

I claim:

1. In a machine for tapering blanks of the type having a platen with a plane surface adapted to support a blank to be tapered, the combination of a stationary frame, an arm having a fixed pivotal connection at its upper end on said frame about an axis located above, and parallel to, the plane surface of said platen, the said axis being positioned above the platen and between the center and the periphery of said platen, a freely rotatable roller, fixedly mounted upon the lower end of said arm about an axis parallel to the axis about which said arm pivots so that as the arm swings about said first mentioned axis said roller is caused to travel along an arcuate path concentric to said first mentioned axis and extending in a direction radially of said platen, the pivot for said arm being positioned above said platen so that a perpendicular line extended from the axis to the plane surface of said platen will join the platen at a position a substantial distance radially outwardly from the center of the platen whereby as the arm swings from the center of the platen outwardly toward the periphery thereof the roller at the lower end of said arm rolls and tapers the blank so that the blank decreases in thickness from the center toward the edge of the blank, and means for causing said roller to engage and roll a taper on the surface of a blank supported on said platen comprising power actuated toggle means positively connected to said arm for swinging said arm about its axis.
2. The combination set forth in claim 1 including means for adjustably moving the pivotal connection between said arm and said frame in a plane parallel to the plane surface of said platen and in a direction generally radially of said platen.

HARRY J. HORN.
